UNITED STATES PATENT OFFICE.

ALEXANDER J. OSTRANDER, OF LYONS, NEW YORK.

STRINGED MUSICAL INSTRUMENT.

1,388,880.

Specification of Letters Patent. Patented Aug. 30, 1921.

Application filed January 26, 1918, Serial No. 213,992. Renewed February 17, 1921. Serial No. 445,851.

To all whom it may concern:

Be it known that I, ALEXANDER J. OSTRANDER, a citizen of the United States, and resident of Lyons, in the county of Wayne 5 and State of New York, have invented certain new and useful Improvements in Stringed Musical Instruments, of which the following is a specification.

The present invention relates to stringed 10 musical instruments, and an object thereof is to provide for automatically maintaining a given pitch in each and every string of such instrument so that the periodic tuning by a piano tuner is rendered unnecessary. 15 Another object of the invention is to provide an instrument having means for maintaining a constant or invariable tension in a string under any change in the total length of such string due to changes in temperature, combined 20 with means for mounting the string so that the effective length of the vibrating portion of the string is maintained constant during the changes in the total length of the string, without producing any friction on the string due to drawing the latter over a bridge piece. A further object is to provide a movable bridge piece which will maintain the vibrating length of a string constant notwithstanding adjustment of the string to 25 maintain a desired tension. Still another object of the invention is to provide a common source of energy which will automatically maintain the pitch of a plurality of strings, preferably all of the strings of the instrument, 30 this common source of energy preferably being so connected to the individual strings that the pitch of any one string may be changed with relation to the others, the connections preferably also being so constructed that, regardless of the initial tension on different strings, a definite per cent. of increase or decrease in tension may be obtained through the variation of the amount of energy.

40 To these and other ends the invention consists of certain parts and combinations of parts, all of which will be hereinafter described, the novel features being pointed out in the appended claims.

45 In the drawings:

Figure 1 is a cross section of a part of a piano showing the method of stringing the instrument and the mechanism for maintaining a given degree of tension in the vibrating 50 portions of the strings;

Fig. 2 is a horizontal section on the line 2—2, Fig. 1;

Fig. 3 is a detail view of the channel plate;

Fig. 4 is a detail view, showing the relative 60 positions of three of the string levers;

Fig. 5 is a detail view of one of the blocks serving as fulcrums for a string lever;

Fig. 6 is a detail view of a modification 65 of the manner of supporting the strings; and

Fig. 7 is a sectional view through another embodiment of the invention.

The invention is herein shown as embodied in a pianoforte, but it will be understood 70 that it is not limited to instruments of this type but may be embodied in other stringed musical instruments.

Referring more particularly to the embodiment shown in the drawings, 1, 2 and 3 75 indicate three wires of a triple unison, these wires being secured in any suitable manner at their lower ends and having their upper ends secured to pins 4 mounted in a manner to be hereinafter more fully described. Below the pins 4 the wires or strings are engaged either by a single bridge piece 5 common to the three wires, as shown in Fig. 4, or separate bridge pieces 5^a for each of the wires 1, 2 and 3, as shown in Fig. 6. 80

These bridge pieces are of novel construction and are mounted on fulcrums or axes 6, permitting said bridge pieces to swing in the direction of the length of the strings or wires, these fulcrums being in the form of 90 knife-edge bearings resting against the bridge support 7 on the wrest plank 8. The bridge pieces 5 have curved faces 9 which are concentric with the axes 6 and bear against one side of the strings or wires to 95 define the length of the vibrating or effective portions of the strings or wires.

Also bearing against the strings or wires are clamp pieces 10 having knife edges 11 resting against the clamp support 12, these 100 clamp pieces also being mounted to turn about the knife edges 11 as axes, and having curved faces 13 for engagement by the strings or wires, the curved faces being concentric with the axes 11. These clamp pieces 105 tend to hold the strings or wires firmly in contact with the curved faces 9 of the bridge pieces 5. It is apparent that any tension or pull on the upper ends of the wires 1, 2 and 3, in the direction of their lengths, will tend 110

to rock the bridge pieces 5 and the clamp pieces 10 about their respective axes 6 and 11, without producing any friction on the wires. At the same time, owing to the curvature 9 of the bridge pieces 10 and to the rocking of the bridge pieces about fixed axes, the effective lengths of the vibrating portions of the wires or strings are not changed but remain constant or invariable, notwithstanding any adjustment of the strings to maintain desired tension.

Another feature of this invention is a mechanism for producing tension in a plurality of strings of a musical instrument of the type mentioned, said mechanism having a common source of energy and being so connected to the different strings that the proper tension is applied to each string for maintaining a given pitch in such string, notwithstanding the effects produced on the instrument due to changes in temperature. The common source of energy which may be any suitable force, in this instance embodies a weight 14 suspended by a rod 15 which at its upper end is pivoted at 16 to a lever 17, in turn pivoted at 18 to a channel plate 19, the function of which will be hereinafter described. This weight or common source of energy acts upon a movable member or plunger 20 of a fluid pressure chamber.

The fluid pressure chamber, in addition to the movable member or plunger, comprises a cylinder 21 held to a supporting head 22 by bolts 23 with an interposed packing 22^a, and also a diaphragm of tubular formation clamped at one end 24 between the cylinder and the head 22, coöperating with the interior walls of the cylinder, and provided with a fold 25, the end 26 of the tubular diaphragm being secured to the plunger 20 beyond said fold. With the plunger 20 a pin point bearing 27 on the lever 17 is engaged so that the force in the weight 14 is communicated to the piston or plunger 20, and through the latter and the diaphragm 25 to a fluid within the chamber of the cylinder 21. From this cylinder 21 a conductor tube 28 leads to the channel plate 19 hereinbefore mentioned. This channel plate extends substantially throughout the length of the piano and has a longitudinally extending channel 29 to which laterals 30 are connected, each lateral 30 also having branches 31 on opposite sides thereof. The channel plate 19 is secured to the rear face of a supporting member 32 which carries a plurality of pressure operated devices. Any suitable fluid may be used for transmitting power from the pressure chamber to the pressure operated devices. The embodiment shown in Figs. 1 to 6, inclusive, employs mercury. I also may use vaseline or a fluid preparation similar to that employed for rendering bicycle tires air tight.

65 Each pressure-operated device comprises,

in this instance, a cylinder 33 and a plunger or piston 34, the piston having a tubular diaphragm secured at one end at 35 to the piston and provided with a fold 36, said diaphragm coöperating with the interior wall 70 of the open-ended cylinder 33 and being folded at 37 about the inner end of the cylinder, the portion 37 lying between the outer wall of the cylinder and a screw-threaded bore in a support 32 so as to form a tight 75 joint between the cylinder and such support 32. The inner end of the cylinder lies directly over one of the branches 31, so that pressure within the pressure chamber or cylinder 33 is communicated to each of the pistons 34.

Connection between each piston or pressure-operated device 34 and the string which it controls may be effected by providing the piston 34 with a knife-edge bearing 38 which 80 coöperates with a lever 39 near the free end of the latter. This lever 39 has a knife bearing 40 which rests against the fulcrum rail 41, the lever being engaged in proximity to its fulcrum 40 by a shackle 42 to which a tie 85 rod or connector 43 is secured. This tie rod has its other end secured to a shackle 44 adjustably mounted on a lever 45 on which the string-securing pin 4 is mounted. The lever 45 has a knife edge 46 which rests upon a 90 shoulder 47 formed on the fulcrum block 48, this fulcrum block, in this instance, having three of such shoulders 47 arranged one above another so that it may act as a support for the three levers 45 of a triple unison. 100 The shackles 42 and 44, being adjustably secured to their respective levers 39 and 45, make it possible to vary the amount of tension applied to the vibrating string without changing the amount of pressure directly 105 exerted by the piston 34, so that should it be necessary to change the pitch of any one string, this can be effected by shifting the shackles 42 and 44 connected to said string. As soon as the proper pitch is secured, the 110 shackles are secured in their adjusted position by the clamping screws 49, and the pitch of the string is dependent entirely on the amount of pressure within the pressure chamber.

In the embodiment shown in Fig. 7, the support 32^a for the pressure operated devices is formed with bores 33^a which act as the pressure chambers for the pressure operated devices. The tubular diaphragm of 120 each pressure operated device has one end 37^a secured at one end to the bore, while the other end 35^a is secured to the plunger 34^a. On the back of the support 32^a a pressure chamber 28^a is formed, this chamber having 125 the bores 33^a opening thereto. Through the top wall of the chamber 28^a a tubular member 21^a is fitted, this tubular member having a beveled lower end and containing a plunger 20^a to which one end of the tubular dia- 130

phragm 25^a is connected, the diaphragm 25^a being constructed similar to other diaphragms in this case. The upper end of the plunger 20^a is engaged by a pin bearing 27^a 5 on a lever 17^a which, by the rod 15^a, connects with a suitable weight. When the fluid matter is viscous, such as vaseline, the action of such vaseline will be slow, so in connection with the fluid pressure chamber 10 there is employed a yielding diaphragm 50 in proximity to the lower beveled end of the tube 21^a, in order that the pressure in said tube will be directed immediately against said wall and the latter will yield. 15 This wall 50 is also common to an air chamber 51 or chamber for some fluid such as air which is more active than the fluid in the chamber 28^a. As the air chamber 51 and the wall 50 extend throughout the length of 20 the pressure chamber 28^a, the air will re-act quickly throughout the length of the chamber, thus rendering the communication of a variation in pressure substantially instantaneous. The air chamber 51 may be provided with an air valve 52 through which the desired pressure of air in the chamber 51 25 may be introduced.

In operation, the pressure chamber and the connections are filled with a suitable 30 fluid, the weight being adjusted to produce a suitable pressure in the pressure chamber. Each string is individually adjusted and pitched by turning the pin 4 and shifting the rod 43 on its levers 39 and 45. Different 35 degrees of tension required are secured approximately by giving greater or less cross sectional areas to the various pistons. When all the strings have been properly tuned or pitched the weight 14 through the pressure 40 operated devices will hold the pitch notwithstanding any effects due to expansion and contraction under changes in temperature. To raise the pitch of the entire instrument, the weight 14 may be increased, or to 45 lower the pitch the weight may be decreased.

From the foregoing it will be seen that there has been provided an improved manner of supporting the wires or strings of musical instruments. Both the length and 50 the tension of the vibrating portion of a string is rendered constant or invariable notwithstanding the expansion or contraction of the total length of the string due to changes in temperature. All of the wires or 55 strings are controlled from a common source of power preferably through fluid as distinguished from mechanical connections. The action of the weight on the pressure chamber is constant and the pressure chamber 60 has fluid connections with pressure-operated devices acting on the strings. Between the pressure operated devices and the strings are arranged mechanical connections which may be so adjusted that any desired 65 tension on a string may be secured, that is,

the action of the pressure device on any string may be increased or decreased to secure the desired pitch. Once this pitch is obtained it will be maintained notwithstanding the effects of changes in temperature, so 70 that the original pitch of the string is maintained. It is apparent also that any increase or decrease in the weight will not impose the same increase or decrease in tension on the various strings but instead the same per 75 cent. of variation in tension will be obtained, thus making it possible to raise or lower the pitch of the instrument as a whole merely by increasing or decreasing the weight.

What I claim as my invention and desire 80 to secure by Letters Patent is:—

1. A stringed musical instrument comprising a plurality of differently tensioned strings and interrelated connections between the strings for maintaining them under tension, said connections having provision for changing the tension of all of the strings simultaneously a like per cent.

2. In a stringed musical instrument, a plurality of differently tensioned strings, and 90 interrelated connections between the strings having fluid means therein for maintaining the strings under proper tension.

3. In a stringed musical instrument, a plurality of differently tensioned strings, interrelated connections between the strings having fluid means therein for maintaining the strings under tension, and means for maintaining a desired pressure in said fluid 95 means.

4. In a stringed musical instrument, a plurality of differently tensioned strings, and interrelated connections between all of such strings having automatically operating means for maintaining a given necessary degree of tension on each string for the correct pitch of the string with relation to the other strings.

5. In a stringed musical instrument, a plurality of differently tensioned strings, and 110 interrelated connections between all of such strings, said connections having automatically operating means for maintaining a given necessary degree of tension on each string for the correct pitch of the string, with relation to the other strings and said connections having means adjustable to vary the pitch of the different strings with relation to each other.

6. In a stringed musical instrument, a plurality of differently tensioned strings and interrelated connections between all of such strings having fluid means therein, and means associated with said connections and adjustable to vary the pitch of any string 120 with relation to the others.

7. In a stringed musical instrument, a plurality of differently tensioned strings, and interrelated connections between the strings for maintaining the strings under tension 130

comprising a common fluid pressure chamber, means for varying the pressure therein, a plurality of fluid operated devices connected with said chamber, one for each of 5 said strings, and adjustable mechanical operated devices between said fluid connections and the strings.

8. In a stringed musical instrument, a plurality of differently tensioned strings, and interrelated connections between the 10 strings embodying a plurality of fluid operated devices and fluid connections between said devices.

ALEXANDER J. OSTRANDER.
